CLAIM

The ornamental design for a deadlock door plate kit, as shown and described.

DESCRIPTION

FIG. 1 is a front view of a deadlock door plate kit showing my new design;

FIG. 2 is a rear view of the deadlock door plate kit;

FIG. 3 is a right side view of the deadlock door plate kit;

FIG. 4 is a left side view of the deadlock door plate kit;

FIG. 5 is a top view of the deadlock door plate kit;

FIG. 6 is a bottom view of the deadlock door plate kit; and,

FIG. 7 is a top front side perspective view of the deadlock door plate kit.
